CENTRIFUGAL PUMP

Charles H. Fox, Cincinnati, Ohio, assignor to The Ahrens-Fox Fire Engine Company, Cincinnati, Ohio, a corporation of Ohio

Application September 19, 1935, Serial No. 41,280

4 Claims. (Cl. 169—24)

This invention relates to fire engines, and in particular, to power-operated pumping engines wherein the pumping units consist of centrifugal pumps.

5 One object of this invention is to provide a fire engine pumping unit composed of a pair of centrifugal pumps operated by independent driving transmissions, but having their intakes and outlets connected to a common source and a common exhaust, respectively, the pumps being capable of operation either individually or combined in series or in parallel.

10 Another object is to provide a pumping unit of the type previously set forth, wherein each 15 pump consists of a centrifugal pump comprising one or more stages.

Another object is to provide a fire engine pumping unit consisting of a pair of centrifugal pumps, a power plant, independent transmissions for driving each pump from the power plant, the pumps being capable of being driven either individually or together, the transmissions being arranged so that the pumps may be started selectively.

20 Another object is to provide a pumping unit composed of a pair of centrifugal pumps in a hydraulic circuit, the intakes of the pumps being adapted to communicate with a source of supply, automatic valve means being arranged to cut off one of the intakes from such a source 25 when the outlet of the other pump is connected in series with its intake, so as to operate the two pumps in series to provide a maximum pressure delivery.

30 In the drawings:

Figure 1 is a plan view of the chassis of the fire engine of this invention, with the various units mounted thereon but with the body and superstructure removed in order to more clearly 35 disclose the various mechanisms.

40 Figure 2 is an irregular cross section through the pumping unit of Figure 1, taken approximately along the line 2—2 thereof.

45 Figure 3 is an enlarged fragmentary view of the diversion valve shown in combination with other elements in Figure 2, the valve being set to connect the two pumps in series.

50 Figure 4 is a view similar to Figure 3, but with the valve set to connect the two pumps in parallel.

Figure 5 is an end view of the pumping unit shown in Figure 1.

55 Figure 6 is a horizontal section taken along the line 6—6 of Figure 5.

Figure 7 is a longitudinal, vertical section

through one of the pumps shown in Figure 1, and taken along the line 7—7 of Figure 1.

Figure 8 is a fragmentary side elevation of the right-hand side of the mechanism shown in Figure 1.

5 Figure 9 is a fragmentary plan view of a portion of the mechanism shown in Figure 1, illustrating the manner of operating the diversion valve.

Figure 10 is a side elevation of a fire engine, 10 with the body and super-structure superimposed upon the chassis shown in Figure 1, illustrating the positions of the various elements of the invention.

Figure 11 is an end elevation of the auxiliary 15 pump employed in the fire engine of this invention.

Figure 12 is a top plan view of the auxiliary pump shown in Figure 11.

Figure 13 is a transverse section through the 20 common intake conduit and the main suction chamber, taken along the line 13—13 of Figure 6.

Figure 14 is a diagrammatic view of the several parts of the apparatus.

One of the problems hitherto encountered in 25 the manufacture of fire-fighting equipment was to provide a fire engine which would be capable of efficiently handling the varying requirements of service. A fire in a high building requires the pumping of water at high pressure. On the 30 other hand, a large fire in a low building requires the application of the maximum quantity of water without the necessity for high pressures. Furthermore, the majority of fires encountered and which the fire engine is expected 35 to extinguish, are of a very small nature, in low buildings or in situations requiring the application of small quantities of fluid at low pressures.

A modern fire engine, however, in order to meet 40 the requirements of the underwriters, must be designed to accommodate the maximum delivery and the maximum pressure specified by the regulations.

To accomplish this the present inventor has found that centrifugal pumps are 45 suitable for pumping fluid to extinguish large or high fires. A centrifugal pump, however, is somewhat inflexible in that it has an unavoidably narrow range within which it operates efficiently.

The centrifugal pump cannot be slowed down in proportion to a requirement for smaller 50 amounts of water, but must be kept up to speeds compatible with certain pressure requirements. Furthermore, the present inventor has found that small jets of water are more satisfactory for extinguishing small fires than the jets of chemicals 55

previously employed. To reconcile all of these varying requirements encountered in fire-fighting was the problem of the present inventor.

To solve this problem the present inventor has provided a fire engine having a pair of centrifugal pumps, together with a small auxiliary pump. These pumps are provided with transmissions and power takeoffs of such a nature that either of the main pumps may be operated individually in order to most efficiently extinguish a fire of medium size. Both of the main pumps may also be operated simultaneously, either in series where high pressures are more important than great volume, or else in parallel where a large volume delivery is more important than a high pressure. The small auxiliary pump is arranged to serve as an exhauster for either of the main pumps, or else as an additional pump for pumping small quantities of fluid either from a tank carried by the fire engine or from an independent source of supply, this being used for very small fires where it would be inefficient or costly to operate either of the main pumps.

Referring to the drawings in detail, Figure 1 shows the central portion of the fire engine of this invention in plan view with the body and other super-structure removed. In this figure it will be seen that the fire engine has a frame with side members 1, upon which is mounted the motor, generally designated 2, having a flywheel housing 3 with side extensions joined to the frame, as at 4. The junctions 4 provide the required points of support of the motor 2. To the rearward side of the flywheel housing 3 is joined a clutch housing 5, which incloses a driving clutch (not shown), whereby the two may be connected to the remainder of the mechanism. This clutch is of a conventional type, and its details together with the details of the engine, form no part of the present invention.

Mounted rearwardly of the clutch housing 5 is the main transmission unit 6, consisting of a standard selective type gear box having the usual arrangement of gears to provide the speeds forward and reverse required for propelling the ordinary vehicle. The main transmission unit 6 is operated by a hand lever 7 in the usual manner, and serves to impart power to a pump drive unit 8 attached to and connected with the main transmission unit 6. The power from the latter is applied in a manner subsequently to be described, either to the propulsion of the vehicle by way of the traction drive shaft 9, or else to the pumps, either individually or in combination through the right-hand pump driving connection 10, or through the left-hand pump driving connection 11. The universal joints 12 and 13 serve as usual to transmit the power through the traction drive shaft 9, under varying angles, to the rear axle of the truck. The disc-type parking brake 14 serves the usual purpose of locking the main traction drive shaft 9.

The pump driving connections 10 and 11 are joined respectively to a pair of main pumps, the right-hand main pump being generally designated 15 and the left-hand main pump 16. Each of these pumps is substantially identical with the other, and a description of one will suffice. The details of these main pumps are shown in Figure 7 and will be described later. The left-hand main pump 16 is connected to a common intake conduit 17 (Figure 5), which terminates on opposite sides of the frame in the intake ports 18. The intake conduit 17 is secured to the frame members 1 by means of

the brackets 19. The right-hand main pump 15 (Figure 5) is provided with an intake conduit 20 (Figures 2 and 5), connected as at 21 to the common suction chamber 48, as will appear later. The intake conduit 20 leads into the casing of the pump 15, as will subsequently appear. The fluid pumped by the first stage of the pump is discharged into the first-stage volute 22, and thence into the cross-over conduit 23, which connects the outlet of the first-stage volute, as at 24, with the inlet 25 (Figure 2) of the second-stage, as at 26.

This fluid is pumped by the second stage of the pump 15 into the second-stage volute 27, the latter being joined, as at 28, to the discharge leader 29. The latter is connected, as at 30, with the common discharge header 31. Attached to the common discharge header are hose gates 32, which vary in number according to the pumping capacity desired. These hose gates 32 are operated by the handles 33 in order to control the flow of fluid into the various lines of hose connected to these hose gates.

The intake 34 of the left-hand main pump 16 is similarly connected, as at 35, to the intake 25 conduit 17, and the fluid pumped by its first stage passes into its first-stage volute 36. The latter is connected, as at 37, to the cross-over 38, this being, in turn, connected, as at 39, to the second stage of the pump 16. The fluid delivered by this second stage passes into the second-stage volute 40, which is connected, as at 41, to the diversion valve casing 42, consisting of a projecting portion of the common discharge header 31.

The diversion valve casing 42 contains the diversion valve member 43 (Figures 2, 3 and 4), having a passageway 44 therethrough. When the valve member 43 is set, in the manner shown in Figures 2 and 3, the discharge of fluid from the left-hand pump volute 40 passes through the valve into the series branch conduit, generally designated 45. The latter consists of the conduit sections 46 and 47, joined to one another at the junction 49 (Figure 2). The series branch conduit 45 is joined at one end, as at 50, to the diversion valve casing 42. At its opposite end it is joined to the main suction chamber 48 (Figure 6). The main suction chamber 48 terminates in the automatic valve chamber 52. The automatic valve chamber 52 contains the automatic valve member 53, serving to close the port 54 leading therefrom into the common intake conduit 17. The automatic valve member 53 is pivoted at 55 to an arm 56, which in turn, is pivoted around the shaft 57 and impelled into a position closing the port 54 under the urge of the spring 58. The intake conduit 20 of the right-hand main pump 15, as previously stated, is connected to the automatic valve chamber 52 at the junction 21 (Figure 13).

The diversion valve member 43 (Figure 2) is rotatably mounted in its casing 42 upon the shaft 59, this shaft carrying at its outer end the skew gear 60. The latter meshes with a pinion 61 mounted upon the shaft 62 and journaled in bearings 63. The opposite end of the shaft 62 is provided with a hand wheel 64. By manually rotating the hand wheel 64 the position of diversion valve member 43 may be varied to connect the 70 main pumps 15 and 16, either in series or in parallel.

As previously stated, the main pumps 15 and 16 are operated independently from the power supply. The main pump 15 is operated through 75

the right-hand pump driving connection 10 from the pump drive unit 8 (Figure 1). The left-hand main pump 16 is similarly driven independently from the left-hand pump driving connection 11, also connected to the pump drive unit 8. The pump drive unit 8 contains sliding gears which are movable in a conventional manner to connect the main transmission unit 6 with either or both of the pump driving connections 10 and 11.

10 The gear shifting for this purpose is accomplished by rotating the shaft 65 through the agency of the hand lever 66 mounted thereon. The hand lever 66 engages a quadrant 67 having five notches 68, 69, 70, 71 and 72 therein (Figure 15 8). By shifting the lever 66 into one of these five notches, as will be explained later, the power from the engine may be connected selectively to the chassis drive shaft 9, to the right-hand pump 15, to the left-hand pump 16, or in a neutral 20 position. The gears in the pump drive unit 8 are prevented from clashing during this shifting by the operation of a vacuum-actuated device 13, which disconnects the clutch within the clutch housing 5 through the connecting arm 14 (Figure 25 1) whenever the lever 66 is shifted to a new position.

The main clutch may be released manually by the operator by means of pressure applied to the clutch pedal 75 (Figure 1). The brakes of the 30 fire engine are applied by pressure upon the brake pedal 76, assisted by the master brake cylinder 77 and the master brake vacuum cylinder 78. The parking brake 14 is applied by operating the hand brake lever 79, (Figure 1) in the ordinary 35 manner. The details of the braking and clutch system, as described above, form no part of the present invention.

An auxiliary pump 80 of the positive displacement type (Figure 1) is driven from the shaft 40 81 emerging from the auxiliary pump power take-off 82, the latter being connected to the main transmission 6. The auxiliary power pump take-off 82, of a conventional type the details of which form no part of the present invention, is operated 45 to connect or disconnect the auxiliary pump 80 from the source of power by shifting the auxiliary pump hand lever 83 (Figure 1). The latter is mounted upon the shaft 84, which is journaled in the casing of the pump drive unit 8 and carries 50 at its opposite end an arm 85. The latter is connected by the connecting rod 86 to an arm 87, mounted upon the auxiliary pump control shaft 88. The latter serves to operate clutch means 55 within the auxiliary pump power take-off 82 to connect or disconnect the auxiliary pump 80 from the power source.

The auxiliary pump 80 (Figures 11 and 12) is of a conventional type, the details of which form no part of the present invention. This pump 60 90 comprises a casing 89 having end plates 90 and 91 secured thereto as by the cap screws 92. The upper side of the casing 89 is provided with a junction 93 arranged for connecting the auxiliary pump intake pipe 94 thereto. The opposite or 65 bottom side of the auxiliary pump 80 contains a similar junction 95, to which is connected the auxiliary pump outlet pipe 96.

The auxiliary pump intake pipe 94 leads to the three-way valve 97, having an operating handle 70 98 (Figure 14). From one of the three connections on the opposite side of this valve the pipe 99 leads to the tank 100. This tank is arranged to contain water, somewhat over one hundred gallons in quantity. The middle connection of 75 the three-way valve 97 is connected to the pipe

101, which leads to the casings of the main pumps 15 and 16. The remaining connection of the three-way valve 97 leads to the pipe 102, which terminates in the hose connection 103. By suitably moving the valve handle 98 the auxiliary pump 80 may be caused to create a suction, drawing in water from the tank 100, or else to create a suction in the casings of the main pumps 15 and 16, thereby setting up the initial draft necessary to cause these pumps to 10 operate or finally to draw in water from the hose connected to the hose connection 103, this hose being connected to a hydrant, pond or other external source of supply. The outlet pipe 96 of the auxiliary pump 80 leads to the hose connection 104. The latter serves for the connection of a small hose which may be used for extinguishing small fires, the fluid being supplied by the pump 80.

The main driving pumps 15 and 16 are of the 20 two-stage centrifugal type shown in longitudinal section in Figure 7. The details of these pumps in themselves form no part of the present invention; hence, a brief description will suffice. The right-hand main pump 15 is chosen for purposes 25 of description, although it will be understood that the left-hand main pump 16 might be similarly described.

As previously described, the main pump 15 is provided with an intake conduit 20, leading to the 30 casing 105 (Figure 7). The latter is provided with a pair of interior chambers, namely, the first-stage chamber 106 and the second-stage chamber 107. Surrounding these chambers 106 and 107 is a water jacket chamber 108. The 35 chamber 108 is connected to the radiator or cooling system of the motor 2 so that the fluid passing through the pump is utilized to assist the cooling system of the motor in warm weather, and the warm water from the radiator is utilized 40 to keep the pumps from freezing in cold weather. The details of this cooling and warming system form no part of the present invention, but are contained in my copending application, Ser. No. 27,404, filed June 19, 1935. 45

The pump casing 105 is provided with end plates 109 and 110, each of these having bores 111 and 112, respectively, serving to receive packings 113 and 114, surrounding sleeves 115 and 116, respectively. Passing through these sleeves 50 is the pump drive shaft 117 having the end portions 118 and 119 thereof rotatably supported by the anti-friction bearings 120 and 121, respectively. The driving end adjacent the bearing 120 is provided with a universal or self-aligning connection, generally designated 122, which serves to compensate for slight changes in alignment or slight errors in assembly. The packings 113 and 114 may be compressed to prevent leakage by turning the glands 123 and 124, respectively, 60 these being locked in their adjusted positions by the latch members 125 and 126, operating in the notches 127 and 128.

The drive shaft 117 is provided with a pair of splined portions 129 and 130, (Figure 7) upon 65 which are mounted the rotors of the pump. The first-stage rotor 131 is mounted upon the splined portion 130 and is provided with a plurality of radially directed arms having passages 132 therethrough. The outer ends of these passages 132 70 open into the chamber within the first-stage volute 22. This volute is connected at the junction 24 to the cross-over 23, which leads to the second-stage volute 27 in the manner previously described. 75

The second-stage rotor 133 is similar in form to the first-stage rotor 131 but is secured to the splined portion 129. Its outwardly directed passages 134 are curved in a direction away from the passages 132 so that the thrusts thereof tend to react upon one another and compensate for end thrust. The outer ends of the second-stage rotor passages 134 open into the chamber within the second-stage volute 21. The latter is connected at the junction 28 to the discharge leader 29 (Figure 1) and this, in turn, is connected to the distribution header 31 in the manner previously described.

The pump drive shaft 117 receives power from the pump driving connection 10, through the tubular drive shaft 135 thereof by way of the universal joint 122. The rotation of the first and second-stage rotors 131 and 133, respectively, causes the fluid to be thrown outwardly into the first and second-stage volutes 22 and 21, the fluid passing onward under pressure thus created.

The traction drive shaft 9 receives bearing support through the agency of a bearing assembly 140, supported by the intake header 17 by means of the right-angled bracket 141 secured thereto (Figures 1, 5 and 8). In this way the intake header 17 serves to support not only one of the pumps, but also the drive shaft 9.

In the operation of the valve mechanism, to connect the main pumps 15 and 16 in series so that the maximum pressure will be obtained, the diversion valve member 43 is rotated by the hand wheel 64 into the position shown in Figures 2 and 3. In this position the fluid is drawn into the left-hand main pump 16 through its intake conduit 34 from the common intake conduit 17. This fluid is placed under pressure by the pump and is discharged from the second-stage volute thereof into the diversion valve chamber 42 (Figure 2). The fluid passes through the diversion valve passage 44, the series branch conduit 45 and the automatic valve chamber 52, upwardly into the intake conduit 20 of the right-hand main pump 15 (Figures 6 and 13). The fluid, which is already under pressure from the left-hand main pump 16, is further subjected to pressure in the right-hand main pump 15, and passes outwardly therefrom through the discharge leader 29 into the distributing header 31. The fluid is distributed from the distributing header 31, through the hose gates 32, into the various lines of hose by turning the valve handles 33 in a conventional manner.

To connect the main pumps 15 and 16 in parallel, whereby to obtain the maximum volume of delivery of fluid, the hand wheel 64 is rotated so that the diversion valve member 43 is set in the position shown in Figure 4, thereby cutting off the series branch conduit 45 from communication with the left-hand main pump 16 (Figures 2 and 4). With the valve set in this position both of the pumps 15 and 16 take in fluid independently. The right-hand main pump 15 draws in fluid through its intake conduit 20 from the automatic valve chamber 52, the automatic valve member 53 opening inwardly (Figure 6) against the urge of its spring 58, to permit fluid to pass from the common intake conduit 17 through the port 54. At the same time the left-hand main pump 16 draws in fluid from the same intake conduit 17 through its intake conduit 34.

Each of the pumps 15 and 16 places the separate quantities of fluid under pressure and discharges these, each through its own volute. The right-hand main pump 15 discharges its fluid

from its second-stage volute 21, through the discharge leader 29 into the distributing header 31 (Figure 1). At the same time the left-hand main pump 16 discharges its fluid from its second-stage volute 40 through the diversion valve 5 passage 44, set in the position shown in Figure 4, into the distributing header 31. The separately pumped quantities of fluid thus unite in the distributing header 31 and are distributed to the various hose lines by way of the hose gates 32. Thus by suitable manipulation of the hand wheel 64 the diversion valve member 43 may be rotated to place the main pumps 15 and 16 in series to produce the maximum pressure at a sacrifice in volume, or to produce the maximum volume delivery at the sacrifice of pressure. This alteration may be made in accordance with the conditions encountered in the particular fire.

It will thus be seen that the pump drive unit 8 and the pump driving connections 10 and 11 are arranged in such a manner that the shifting of the hand lever 66 causes both pumps to be operated, either individually or collectively. The pump drive unit 8, however, is so arranged as to prevent the simultaneous starting of both of the main pumps 15 and 16, and to permit these pumps to be started only in succession to one another.

In the operation of the mechanical driving connections of the main pumps 15 and 16, when the lever 66 is shifted into the first notch 68 (Figure 8), power from the main transmission 6 is transmitted through the traction drive shaft 9 and the universal joints 12 and 13 to the rear axle of the truck, thereby propelling the truck. With the lever 66 in the second notch 69 the drive connection is broken between the traction drive shaft 9 and the main transmission 6, thereby nullifying the transmission of power for the purpose of propelling the truck, yet permitting the transmission of power to the pump driving units.

With the lever 66 in the third notch 70 the pump driving connection 10 is operatively connected to the main transmission 6 through the pump drive unit 8, thereby placing the right-hand main pump 15 in operation. With the lever 66 in the fourth notch 71, both of the pump driving connections 10 and 11 are placed in communication with the main transmission 6 through the pump drive unit 8. This causes both pumps to be placed in operation. With the lever 66 in the fifth notch 72 the right-hand pump connection 10 is placed out of operation, and the left-hand pump connection 11 placed in operative communication with the transmission 6 through the pump drive unit 8. This causes the left-hand pump 16 alone to operate.

When the lever 66 is shifted it passes through a neutral zone. Coincident therewith the driving clutch within the clutch housing 5 is released by the force of the vacuum-actuated device 73, as previously explained. Consequently, the shifting through the various positions is effected without clash of the gearing, and when the lever 66 reaches a new notch the drive clutch is thereby closed, communicating power from the engine to the main transmission 6.

It will be observed from the foregoing disclosure that the pump driving connections 10 and/or 11 may be operated either simultaneously with the truck drive shaft 9, as well as independently thereof and independently of one another. This result is effected through the shifting of the hand lever 66 into the five notches 68 to 72, previously discussed. At the same time

it will be obvious that the shifting of the lever 83 may likewise be controlled to cause the power take-off 82 and the auxiliary pump 80 to be operated from the main transmission 6 while the truck is either stationary or in motion. Consequently, the pumping units of the fire engine may be operated either while the engine is stationary or in motion. This enables the use of the fire engine in extinguishing fires which must be followed up, such as grass or brush fires.

10 It will be understood that I desire to comprehend within my invention such modifications as come within the scope of my claims and my invention.

15 Having thus fully described my invention, what I claim as new and desire to secure by Letters Patent, is:

20 1. In a fire engine, a major pump, a tank, an auxiliary pump, means for selectively connecting said auxiliary pump to exhaust from said major pump or to withdraw fluid from said tank, and power means for selectively applying power to said major pump or to said auxiliary pump individually or collectively.

25 2. In a fire engine, a pair of major centrifugal pumps having intakes and outlets, an auxiliary pump, a tank, transmission mechanism for applying power selectively to said pumps either individually or collectively, valve means for selectively connecting said auxiliary pump to exhaust from said major pumps or to withdraw fluid from said tank, diversion valve means and a cross conduit associated therewith extending from the outlet of one of the major pumps to the intake 30 of the other major pump to connect the discharge

of said major pumps in series or in parallel, and check valve means arranged to control the direction of flow from the outlet of the first pump and adapted to prevent flow out of the intake of the second pump.

3. In a fire engine, a pair of major centrifugal pumps having intakes and outlets, an auxiliary pump, a tank, transmission mechanism for applying power selectively to said pumps either individually or collectively, valve means for selectively connecting said auxiliary pump to exhaust from said major pumps or to withdraw fluid from said tank, diversion valve means and a cross conduit associated therewith extending from the outlet of one of the major pumps to the intake 15 of the other major pump to connect the discharge of said major pumps in series or in parallel, and check valve means arranged to control the direction of flow from the outlet of the first pump and adapted to prevent flow out of the intake of the second pump, and control means for said transmission mechanism and said diversion valve means arranged in close proximity to one another, whereby to facilitate the control of said fire engine from a single station.

25 4. In a fire engine, longitudinal frame members, a tank mounted above said frame members, a pair of major pumps mounted between said frame members, an auxiliary pump below said tank, and means for selectively connecting the 30 inlet of the auxiliary pump to the major pumps to cause the priming of the major pumps or to said tank to withdraw fluid therefrom.

CHARLES H. FOX. 35
